UNITED STATES PATENT OFFICE.

HORACE M. CAKE, OF PHILADELPHIA, PENNSYLVANIA.

PROPELLUTION MECHANISM.

Application filed July 6, 1918. Serial No. 243,523.

To all whom it may concern:

Be it known that I, HORACE M. CAKE, a citizen of the United States, residing at Philadelphia, in the county of Philadelphia and State of Pennsylvania, have invented certain new and useful Improvements in Propulsion Mechanism, of which the following is a specification.

This invention relates broadly to propulsion and more specifically to mechanism for balancing and stabilizing propelling systems.

The principal object of the present invention is a mechanism for propelling torpedoes, airships, and the like, by rotary screw propellers driven in such manner as to overcome any tendency of the propeller action to cause the torpedo, airship, or the like, to rotate on the axis of the propeller.

20 A still further object of the present invention is a mechanism as specified wherein the invention is characterized by rotating a pair of screw propellers in opposite directions and compensating the forces absorbed by the propellers in such manner that each propeller at all times absorbs one-half of the driving power.

A still further object of the present invention is a mechanism as specified and wherein the forces to be absorbed by the propellers are delivered through compensating mechanism which transmits the energy directly to one propeller and through reversing gearing to the other propeller, whereby the propellers are driven in opposite directions through the compensating devices so that vibrations due to the passing of propeller blades on opposing propellers are not transmitted directly to the driving shaft but are absorbed through the functioning of the compensating mechanism and by means of the frame work.

More specifically one mechanism for carrying out my invention comprises a head, directly connected to the driving or power shaft, and carrying compensating gears. One side of these gears is directly connected to a bevel gear on the propeller shaft for the outer propeller, and the other side thereof is connected with a bevel gear which transmits through a casing to reversing gears which drive a tubular shaft carrying the inner propeller, so that the entire system comprises a pair of oppositely driven propellers rotating on a common axis and

receiving power through a differential compensating gearing.

Other and further objects of the present invention will in part be obvious and will in part be pointed out hereinafter in the specification following by reference to the accompanying drawings forming a part thereof.

The figure of the drawing is more or less diagrammatic and shows a portion of the construction in section in order to more clearly illustrate the relation of parts.

In the art of screw propellers it is well recognized there is a tendency of a single screw propelled ship, torpedo, aeroplane, or the like, to rotate on the axis of the propeller shaft and opposite to the rotation of the propeller itself. This effect is partly due to reaction on the propeller blades, partly due to the impossibility of making theoretically true propellers for all conditions of speed, and partly due to other causes well known in the art. Attempts have been made to overcome the foregoing difficulties by using twin screws rotating on independent axes; and also attempts have been made to eliminate the foregoing difficulties by providing a pair of oppositely rotated positively driven screws revolving about a common axis. The latter mechanism is most commonly employed for propellers for torpedoes. Neither of the proposed constructions completely overcome the difficulties specified and in both cases additional vibration is introduced. In propellers rotating in opposite directions around a common axis, vibration is accentuated because each time the blades on one propeller pass into the zone of water disturbed by the blades of the other propeller, a different stress condition is established, and where the propellers revolve at high speed the vibration

due to this condition is greatly increased and absorbs a large amount of the driving energy. Furthermore because of the impossibility of making theoretically correct propellers as to pitch, balance, etc., it is difficult and in practice is substantially impossible to provide a pair of positively driven propellers which will not rotate the body of a torpedo around its own axis when it is being driven through the water.

To overcome the difficulties of the known art and to provide a construction for eliminating vibrations due to propeller designs,

and water or air disturbances, the invention which will more specifically be described hereinafter, comprises broadly the arrangement of a pair of axially aligned propellers of opposite pitch mounted in such manner as to receive their driving power through a differential gearing and reversing gearing so that one-half of the horsepower of the driving forces rotates one screw propeller in one direction and the other half of the driving power rotates the other screw propeller in the opposite direction. By this construction it will be noted that when any unbalanced condition exists as to one propeller the surplus force producing the unbalanced condition is transmitted immediately through the differential gearing to the other propeller so that at all times there is true compensation between the propellers without transmitting the compensatory forces or stresses to the driving shaft. This fact tends to relieve the driving shaft of forces which otherwise would cause undesirable vibration. It will also be noted that by this construction if there is a tendency of the torque of either propeller to preponderate over the other propeller in such manner as would cause a torpedo, or the like, to rotate on its own axis where the propeller is positively driven without reciprocal action, such preponderance is immediately absorbed by being distributed between the propellers. Therefore there is no turning element or function which tends to rotate the boat, torpedo, airship, or the like, around the axis of the propeller shaft, where this invention is used.

Referring now more particularly to the drawings the drive shaft 1 carries a transmission head 2 on which is mounted a pair of compensating gears 3. The compensating gears on one side engage a bevel gear 4 that is integral with a collar 5 that is free to rotate around the drive shaft 1. This collar 5 carrying the bevel gear 4 is secured to a housing 6, by means of machine screws or the like. This housing terminates in a reversing bevel gear 7 which engages one side of a pair of idler gears 8 mounted to rotate on stubshafts 9 that are anchored in the stationary member 10 which is secured to a part of the frame work 11 of the torpedo, ship, or other construction, carrying this propelling mechanism. The compensating gears 3 are also in engagement with a bevel gear 12 which is secured to a propeller shaft 13. The idler gears 8 also engage a bevel gear 14 which is mounted on a tubular propeller shaft 15 adapted to rotate about the propeller shaft 13. The tubular propeller shaft 15 carries a propeller 16 having its blades pitched in one direction and the propeller shaft 13 carries a propeller 17 having its blades pitched in the opposite direction.

It is obvious from the foregoing that power from the driving shaft 1 will be transmitted equally to the propellers 16 and 17, one half of the power going to each propeller. In view of this fact it is also obvious that the resistance on these propellers tends to be equal at all times. Now since the pitch of the blades on propeller 16 is opposite to the pitch of the blades on propeller 17, and since the propellers rotate in opposite directions it follows the driving reactions on the propellers are equal and opposite so that the system is rotatively balanced on the axis around which the propellers revolve. Furthermore since the balancing of the otherwise unequal conditions is accomplished by energy transference from one propeller to the other, the main driving shaft is relieved from stresses that would otherwise dissipate a portion of the driving energy. This results in a balanced cushioning action which renders the reaction against the main driving shaft smooth and even and is a further reason for obviating shocks and vibrations as previously specified.

It is obvious that the specific constructions herein disclosed may be varied somewhat without departing from my invention and therefore I desire that it shall be understood that the disclosure herewith is illustrative and not to be taken in the limiting sense.

Having thus described my invention what I claim is:

1. In a propulsion mechanism in combination, a driving shaft, a transmission head carried on said driving shaft, compensating gears upon said transmission head, a face plate carrying thereon a beveled gear in engagement with the compensating gears, a tubular shaft, a propeller on said tubular shaft, a casing secured to said face plate, reversing gearing operatively connecting said casing and said tubular shaft, a cylindrical shaft mounted within said tubular shaft, a propeller carried upon said cylindrical shaft, and a beveled gear on the cylindrical shaft and in engagement with the compensating gears; the driving shaft, the tubular shaft, and the cylindrical shaft, all being in axial alignment.

2. In a propulsion mechanism in combination, a driving shaft, a transmission head, compensating gears carried by said transmission head, a cylindrical shaft, a tubular driven shaft, operative means connecting said tubular shaft with said compensating gears, said operative means including reversing gearing connecting said cylindrical shaft with said compensating gears to drive said cylindrical shaft in the opposite rotative direction to which said tubular shaft is driven, a propeller carried upon said tubular shaft and a propeller carried upon said cy-

cylindrical shaft; the driving shaft, the tubular shaft and the cylindrical driven shaft all being in axial alinement.

3. In a propulsion mechanism in combination, a driving shaft, a transmission head carried by said driving shaft, compensating gears carried on the transmission head, beveled gears engaging said compensating gears on diametrically opposite sides, a tubular shaft, a propeller on said tubular shaft, reversing gearing, a cylindrical shaft mounted within said tubular shaft, a propeller carried on said cylindrical shaft, one of said beveled gears being operatively connected with said tubular shaft through said reversing gearing, and the other of said beveled gears being operatively connected with said cylindrical shaft; the driving shaft,

the tubular shaft and the driven cylindrical shaft all being axially alined.

4. In a propulsion mechanism in combination, a driving shaft, two driven shafts, screw propellers carried on said driven shafts, reversing gearing, and compensating means operatively connecting said driving shaft with one of said driven shafts independently of said reversing gearing and operatively connecting said driving shaft through said reversing gearing to the other driven shaft to drive the driven shafts in opposite directions, the blades of the screw propellers being pitched in opposite directions; the driving shaft and both driven shafts being in axial alinement.

HORACE M. CAKE.
